UNITED STATES PATENT OFFICE.

ALEX BLACKSTONE, OF NEWARK, NEW JERSEY.

DESIGN FOR A MEDICINAL TABLET.

59,950.

Specification for Design.

Patented Dec. 13, 1921.

Application filed May 19, 1921. Serial No. 470,909. Term of patent 7 years.

To all whom it may concern:

Be it known that I, ALEX BLACKSTONE, a citizen of the United States, residing in the city of Newark, in the county of Essex and State of New Jersey, have invented a new, original, and ornamental Design for a Medicinal Tablet, of which the following is a specification, reference being had to the accompanying drawings, forming a part thereof.

In the drawings,

Figure 1 represents a plan view of a medicinal tablet showing my new design.

Fig. 2 represents a transverse section of Fig. 1 taken on line $x-x$, looking in the direction indicated by the arrow.

I claim:

The ornamental design for a medicinal tablet, as shown.

ALEX BLACKSTONE.
